METHOD OF JOINING STRIP

John E. Nielsen, Downers Grove, Ill., assignor to Reynolds Metals Company, Richmond, Va., a corporation of Delaware

Filed July 28, 1960, Ser. No. 45,883

5 Claims. (Cl. 29—59)

This invention relates to a method for joining sheets. More particularly this invention relates to a method for joining superimposed sheet members wherein portions of the sheet members are deformed to serve as fasteners.

Strips of sheet materials may often be joined by staples or other simple fastening devices. However, in the non-ferrous metallurgy arts, for example, where contaminants such as staples cannot be tolerated, no completely satisfactory system has heretofore been developed for joining sheet materials. The joints formed between the strips usually must be quite strong and, where the strips are joined during rolling or other continuous processes, the joints must be rapidly made. Several methods have been devised whereby portions of the strips of sheet material are superimposed and segments of the superimposed portions are then partially punched to deform the material in one direction. The deformed portion is then coined or swaged so as to overlie the rest of the sheet material. Subsequently the deformed portion is flattened to lie in substantially the same plane as the superimposed sheets with the coined or swaged parts overlapping the rest of the sheets. At times, the coining or swaging operation is done concurrently with the flattening operation with complicated spring dies and punches. Up to the present, it has been necessary severely deform the superimposed sheets as a first step and then to severely coin or swage the deformed portion. Accordingly, the prior methods, generally speaking, have been applicable only when joining sheets having a fairly narrow range of thicknesses and comparatively high ductility.

An object of this invention is to provide a method for joining strips of sheet material by controlled steps of deforming the sheet material which may be applicable to various thicknesses of sheet material having various degrees of ductility.

For a better understanding of this invention and its other objects, advantages and details, reference is now made to the present preferred embodiment of the invention which is shown for purposes of illustration only in the accompanying drawing. In the drawing:

FIGURE 1 is a partial perspective view of a pair of sheet members which are to be joined in accordance with the method provided by this invention.

FIGURE 2 is an end view of the sheet members of FIGURE 1 illustrating diagrammatically the manner in which the sheets are to be initially deformed.

FIGURE 3 is a view similar to FIGURE 2 illustrating the manner in which the punches in FIGURE 2 have completed the initial deformation of the sheets.

FIGURE 4 is a partial perspective view of the sheets of FIGURE 1 after initial deformation.

FIGURE 5 is a diagrammatic perspective view showing a pair of die members used in the second deforming or flattening stage in accordance with the method of this invention.

FIGURES 6, 7 and 8 illustrate diagrammatically the manner in which the die members of FIGURE 5 are used to flatten the deformed portions of the sheets.

FIGURE 9 is a partial perspective view of the sheets of FIGURE 1 as they appear after being joined in accordance with the system described hereinafter.

FIGURE 10 is a sectional view of a pair of fastened sheets taken along lines 10—10 of FIGURE 9.

2

In accordance with this invention, a pair of sheets such as members 10 and 12, are first partially superimposed at their ends, as shown in FIGURE 1. The sheets 10 and 12 may be non-ferrous metals, such as aluminum, but the invention disclosed herein could be used in joining other types of sheet materials. The superimposed portions of the sheets 10 and 12 are then placed between a row of opposed, interdigitating punches 14 and 16 as shown in FIGURE 2. The purpose of the punches 14 and 16 is to form a laterally extending row of alternate upwardly and downwardly directed hollow protuberances by displacing adjoining portions of the two sheets in opposite directions into a sinusoidal wave-like pattern. Considering the portions of the sheets which form the upwardly directed protuberances 20 in FIGURE 3, it is apparent that the punches 16 displace superimposed portions of each sheet upwardly so that the bottom face of the lower sheet 12 extends above the plane of the top face of the upper sheet 10. Since the punches 14 interdigitate with the punches 16, the immediately adjacent portions of the sheets are deformed into oppositely directed protuberances 22. Each protuberance 20, 22 is separated from the adjoining protuberances by a longitudinal shear line 24 cut into the sheet members by the adjacent edges of the punches 14 and 16. While the material between pairs of shear lines 24 is stretched to form the protuberances, the material does not split or crack except along the shear lines 24 because the punches 14, 16 have comparatively smooth contours.

The shape of the protuberances 20, 22 is of considerable importance. Each protuberance has a central arch 26 extending laterally of the sheets and semi-circular side panels 28. The panels 28, which are integral with the sheet members, extend inwardly of the protuberances so that the arches 26 are narrowest at their crests. The sloping sides of the arches 26 extend at an approximately 30° angle from the plane of the sheets and terminate in sheared marginal edges 30. The edges 30 of the protuberances 20 extend above the top surface of sheet 10 while the edges 30 of the protuberances 22 extend below the bottom surface of the sheet 12. The sloping sides of the arches 26 are advantageous in that the degree of deformation of the sheets is minimized. Also the sheets may be securely joined without the necessity of a coining or swaging operation upon flattening as will be further discussed below.

It is thus seen that a lateral row or stitch of identical protuberances 20, 22 extending alternately in opposite directions between a plurality of parallel shear lines 24 is formed in the superimposed sheets. Only one more step is required to join the sheet members, namely that of flattening the protuberances to form a plurality of adjoining fastening devices.

The protuberances are flattened in two stages, using a pair of finger dies 32, 34 shown most clearly in FIGURE 5. One half of the working surface of each die 32, 34 is planar while the other half is provided with a row of coplanar fingers 36 extending along one edge thereof, each finger 36 being separated by depressions 38. The two dies 32, 34 are arranged such that the fingers 36 of die 34 lie beneath the planar surface of die 32 while the planar surface of die 34 lies beneath the fingers of die 32. As diagrammatically illustrated in FIGURES 6, 7 and 8, the finger dies 32, 34 are used to consecutively flatten first the top row of protuberances 20 and then the bottom row of protuberances 22. Initially the sheets 10 and 12 with the protuberances 20, 22 formed therein are placed between the dies 32, 34 as shown in FIGURE 6. The fingers 36 of die 34 extend under the protuberances 20 to support the sheets 10 and 12 beside the protuberances while the depressions 38 are sufficiently wide to receive the protuberances 22. As shown in FIGURE 7,

the die 32 is lowered to flatten the protuberances 20. The superimposed sheets are then shifted to occupy the position shown in FIGURE 8 wherein the flattened protuberances 20 extend within the depressions 38 of die 32 while the protuberances 22 are flattened by being squeezed between the flat surface of die 34 and the fingers 36 of the die 32.

The final result of the flattening operations is shown in FIGURES 9 and 10. Each of the protuberances 20 have been flattened to form generally rectangular fastening elements 120 while each of the protuberances 22 have been flattened to form generally rectangular fastening elements 122. As the protuberances 20 are flattened, the sheared edges 30 thereof expand outwardly to form arcuate end flanges 124 extending beyond the adjacent shear lines. Afterwards, upon flattening of the protuberances 22, the sheared edges thereof form arcuate end flanges 126 which extend beyond the original shear lines to overlap the adjacent fastening elements 120. Each of the fastening elements 120, 122 then, comprises a rectangular portion and a pair of arcuate end flanges projecting from opposite sides of the rectangular portion. The overlap is produced by two factors. Since the material forming the protuberances 20, 22 stretches upon initial deformation of the sheet members, the sheared edges 30 tend to expand outwardly causing a portion of the overlap. The overlap is increased since the edges 30 also move upwardly and outwardly as the sloping sides of the arches 26 are flattened. Generally it has been found that the increased overlap due to upward and outward movement of the sheared edges is equal to about half the thickness of the sheets 10 and 12. Thus, a separate coining or swaging operation is unnecessary because of the special construction of the punches and the corresponding shape of the protuberances 20, 22.

The comments so far regarding the fastening elements 120 and 122 have been directed to the fact that the sheared edges of each protuberance expand laterally so that adjoining fastening elements overlay to a considerable extent. It should be noted that the semi-circular edges of the panels 28 will resist flattening more than the arches 26. The sloping sides of the arches 26, then, will rotate and expand outwardly more easily. Also, initially the crest of each protuberance will buckle slightly before the semi-circular edges of the panels 28 flatten, thus causing a very slight oval depression centrally of each flattened protuberance. Since the semi-circular edges of the sides 28 are comparatively sharp and since an oval depression is formed centrally of the flattened protuberances, the fastening elements 122 and 120 will be slightly corrugated, as indicated by lines 130 in FIGURE 9. The effect of the slight corrugation is to stiffen the fastening elements.

The fastening elements 120, 122 then are quite advantageous in that they provide a strong joint both laterally and longitudinally of the sheet members. The overlap between adjoining fastening members is sufficient to provide a strong, continuous joint. If it is desired to have either the top or the bottom of the joints coplanar with the top or bottom sheet respectively, it is possible to manipulate the finger dies 32, 34 so that only one row of fastening elements, that is either elements 120 or 122, extend out of the plane of the sheet members. Usually, however, this is unnecessary.

It will be obvious to those skilled in the art that the protuberances 20, 22 could be flattened in other ways. For example, the superimposed sheets could be placed between flat die faces which are actuated to simultaneously flatten all of the protuberances. In practice, however, the resulting joint is not always satisfactory. In the absence of a support, such as that provided by the finger dies 32, 34 for the sheet members in the area of the protuberance being flattened, the protuberance will buckle in an irregular wave-like fashion. When adjacent protuberances are flattened simultaneously by the flat faces of opposed die

members, the sloping sides of adjacent protuberances will buckle, causing some of the adjoining sheared edges to partially abut. Of course, in the event the adjoining sheared edges do abut, they cannot overlap, so the resulting joint is thereby weakened. For this reason it has been found expedient to flatten only the upwardly or downwardly directed protuberances simultaneously and otherwise support the opposite side of the sheets during the flattening operations.

It is thus seen that a pair of sheet members may be rapidly and tightly joined following the simple steps specified above. Prior to this invention, it has been thought necessary to separately coin or swage the edges of the deformed material either as a completely separate step or during the flattening operation by means of complicated spring punches or the like. However, with this invention, no separate coining or swaging operation is required to form the fastening elements 120, 122 due to the shape of the displaced protuberances formed in the sheet members. As noted earlier, the initial punching operation does not severely deform the sheet members. Accordingly, the steps described above may be applied to various thicknesses of comparatively brittle metals as well as various thicknesses of metals having a high ductility. It has also been found that the pressure required to produce the protuberances is comparatively small so that it is possible to punch an entire row of protuberances simultaneously. Therefore, the above steps may be performed rapidly with relatively simple equipment.

While I have illustrated and described a present preferred embodiment of the invention, it will be recognized that the invention may be otherwise variously embodied and practiced within the scope of the following claims.

Having thus described my invention, I claim:

1. In a method for joining sheet members composed of metal or like material, the steps of displacing adjoining superimposed portions of the members inwardly from the ends thereof to form adjoining, oppositely directed hollow protuberances; simultaneously shearing the members between said protuberances to provide a shear line defining the common marginal edges thereof and stretching the displaced portions in a direction perpendicular to said shear line, the adjoining sides of said protuberances extending angularly toward the plane of the sheet members from opposite sides thereof in substantially tangential relation to each other and terminating in the sheared edges; and flattening said protuberances whereby said edges expand outwardly in overlapping relationship.

2. A method for joining sheet members composed of metal or like material, comprising the steps of displacing adjoining, superimposed portions of the members inwardly from the ends thereof to form a row of hollow protuberances extending alternately from opposite sides of the sheet members, simultaneously shearing the members at the juncture between adjacent protuberances and stretching each of the displaced portions intermediate the sheared edges; each of said protuberances having sloping sides terminating in the sheared edges; and flattening the protuberances whereby the edges of adjoining sloping sides thereof expand outwardly to form a row of fastening elements having overlapping portions.

3. The method of claim 2 in which the protuberances extending in one direction are flattened prior to the flattening of the protuberances extending in the opposite directions.

4. A method for joining a pair of sheet members composed of metal or like material, comprising the steps of superimposing the ends of said members, punching the members inwardly from the ends thereof to form a lateral row of alternately oppositely directed adjoining protuberances by means of a pair of rows of interdigitating punches extending laterally of the members, each adjacent pair of punches having cooperative shearing edges, and advancing the punches so as to shear the members along the juncture between adjacent protuberances, there-

by providing a longitudinal shear line separating said protuberances at their common marginal edges, each of said protuberances including a central arch having sloping sides terminating in said marginal edges; and flattening the protuberances whereupon the edges of adjoining sloping sides expand laterally in overlapping relationship.

5. The method of claim 4 in which the protuberances extending in one direction are flattened before the protuberances extending in the opposite directions are flattened, and which further includes the steps of supporting one side of the sheet members adjacent the protuberances

while the protuberances on the other side are being flattened.
